VENTING DEVICE FOR GASOLINE TANKS

Raymond L. Aumack, Cranford, N. J.

Application May 7, 1934, Serial No. 724,371

6 Claims. (Cl. 277—45)

This invention relates to venting devices, and more particularly to venting devices for use in connection with tanks and storage receptacles for volatile and explosive liquids.

it to be screwed into a tank 7 which contains a volatile and explosive liquid such as gasoline. The upper portion of the member 5 is externally threaded and is provided with a plurality of spaced recesses 27 for a purpose hereinafter described.

5

5 In the storing and transportation of gasoline and similar volatile liquids, it is essential that means be provided to prevent excessive pressures in the tanks occasioned by agitation of the liquid or by heat. It is also necessary to provide
10 means to admit air to the tanks during the draining of the tank. Heretofore, venting devices have been provided for continuously venting tanks to give relief from excessive gaseous pressures; but such valves are objectionable in that
15 they allow continual evaporation of the volatile liquid even when the gaseous pressure is not excessive. Such continual evaporation is wasteful, and in large tanks the loss resulting therefrom is appreciable.

The upper edge of the inner wall of the member 5 is bevelled at 8 to provide a seat for a valve 9 which has a downwardly extending portion 10 provided with a plurality of spaced ribs 11 for the purpose of guiding and properly positioning the valve on its seat. The downwardly extending portion 10 and the valve 9 have an aperture therethrough and the lower edge of the inner wall of the portion 10 is bevelled at 12 to provide a seat for a valve 13 which is attached to a stem 14 extending upwardly through the aperture in member 10 and valve 9. The stem 14 is encircled by a coiled compression spring 15 which bears against a nut 16 threaded to the upper end of the stem 14, the spring 15 also bearing against a disc 17 forming a part of a guide frame 18 integral with the valve 9, the valve stem 14 passing freely through the disc 17.

15

20 It is an object of this invention to provide a venting device for gasoline tanks which allows no leakage or waste of the volatile liquid by evaporation except when the gaseous pressure exceeds a predetermined amount.

Resting upon the valve 9 and encircling the guide frame 18 is a coiled compression spring 19 which engages a cap 20, the latter being screwed onto a casing 21, which in turn threadedly engages at its lower end the member 5. 25

25 A further object is the provision of a venting device for tanks for volatile and explosive liquids which automatically allows the vapor to escape when the gaseous pressure exceeds a predetermined amount; and also automatically allows air to enter the tank at atmospheric pressure when the tank is being drained.

30

The cap 20 is provided with a passage 22 in which the coil spring 19 is positioned, said passage being closed by a disc of wire gauze 23 and the latter is covered by a plug 24 of fusible metal.

A further object is the provision of a venting device for gasoline tanks equipped with a fusible disc to prevent explosions in the case of fire, said valve also being provided with a fire screen or wire gauze to prevent flame from entering the tank in the event that the heat is sufficient to melt the fusible disc.

In operation, the tension of the spring 19 is adjusted by screwing the casing 21 on the member 5. When the gaseous pressure in the tank 6 exceeds a predetermined amount the valve 8 will be moved upwardly against the action of the spring 19 to allow the evaporated liquid to escape upwardly through the spaces between the ribs 11, thence between the valve 8 and seat 8 and thence downwardly and outwardly through the recesses 27. 15

These and other advantageous objects, which will later appear, are accomplished by the simple and practical construction and arrangement of parts hereinafter described and exhibited in the accompanying drawing, forming part hereof, and in which:

When it is desired to drain gasoline or similar fluid from the tank, it is essential that some means be provided for admitting air at atmospheric pressure to the tank, and for this purpose I have provided the valve 13, which automatically opens against the action of spring 15 when liquid is being drained from the tank. When the valve 13 is moved downwardly, air passes upwardly through the recesses 27 into the casing 21 at atmospheric pressure and downwardly into

the tank through the aperture in the downwardly extending portion 10 of the valve 9.

In the event of a fire, the hazard incident to escaping gasoline vapor resulting from gaseous pressure caused by intensive heating of the tank due to the fire is prevented by a fusible disc 24 which is designed to melt between 110° F. and 150° F. When the disc 24 is melted, the gasoline vapors will pass outwardly through the fire screen or gauze wire 23, and if a flame is present, such vapors will burn above the wire gauze, but the flame will not enter the casing 21.

It will be noted that gasoline vapors are allowed to escape only when the gaseous pressure in the tank exceeds a predetermined amount, that is, when the valve 9 is raised off its seat 8 against the action of the spring 19. At all other times there will be no leakage or waste of the volatile liquid by evaporation, as the valve 9 is maintained tightly seated by the spring 19.

The casing 21 is provided at its lower end with a set screw 21a adapted to engage the member 5 to fix the casing thereon. The set screw 21a is preferably countersunk in the casing 21, as clearly shown in Fig. 2, so that it may be sealed, as shown in Fig. 2, to prevent tampering therewith. In order to further adjust the casing 21 on the member 5 it will be necessary to first break the seal, and then loosen the set screw.

From the above description it will be seen that I have provided a simple and effective venting device for gasoline tanks which allows vapors to escape only when the gaseous pressures exceed a predetermined amount, thereby preventing waste and also preventing the exhaust of disagreeable and hazardous fumes continually as heretofore has been the case with venting devices of this type. It will also be noted that my device has few parts and is capable of reliable automatic action for relieving gaseous pressures in the tank, or for the purpose of allowing air to enter the tank at atmospheric pressure when the tank is being drained.

The foregoing disclosure is to be regarded as descriptive and illustrative only, and not as restrictive or limitative of the invention of which obviously embodiments may be constructed including many modifications without departing from the general scope herein indicated and detailed in the appended claims.

Having thus described my invention, what I claim as new and desire to secure by Letters Patents, is:

1. In a venting device for gasoline tanks, a tubular member having a reduced portion externally threaded to enable it to be screwed into a tank, the upper edge of the inner wall of said member being bevelled to provide a valve seat, a first valve resting on said seat and having a downwardly extending portion provided with a plurality of spaced ribs, resilient means for maintaining said first valve on its seat, said ribs slidably engaging the inner wall of said member, the lower edge of said downwardly extending portion being bevelled to provide a valve seat, a second valve engaging said last mentioned valve seat, a valve stem connected to said second valve and extending upwardly through the downwardly extending portion, resilient means for maintaining said second valve on its seat, and a casing threadedly engaging the external wall of said member, said casing enclosing the resilient means of said valves, and the external wall of said member having a plurality of vertical recesses communicating with the interior of the casing.

2. In a venting device for gasoline tanks and the like, a tubular member having the upper edge of the inner wall thereof bevelled to provide a valve seat, a first valve engaging said seat, means for attaching said member to a gasoline tank, a casing threadedly engaging the exterior of said member, a cap threadedly connected to the upper end of said casing, a compression spring bearing against said first valve and said cap to prevent opening of said valve until a predetermined force has been exerted thereon, said first valve having a downwardly extending portion provided with a plurality of spaced longitudinal ribs and having a bevelled edge to provide a second valve seat, a second valve engaging the second valve seat, and having a valve stem extending upwardly into the casing, resilient means to maintain the second valve on its seat but to allow said second valve to open by atmospheric pressure when the tank is being drained, said tubular member having a plurality of recesses on its outer surface communicating with the interior of the casing, said cap having a passage therein, a fire screen positioned in said passage, and a disc of fusible metal closing said passage.

3. In a venting device for gasoline tanks and the like, a tubular member having a plurality of external recesses and provided with means to enable it to be attached to a gasoline tank, a casing threaded to said tubular member, and communicating with said recesses, valve means normally closing said tubular member to prevent the escape of the evaporated gasoline until a predetermined pressure thereof has been reached, and a second valve means associated with the tubular member to allow air to enter the tank when it is being drained, both of said valves opening into said casing, said casing having a passage therein covered by a wire gauze serving as a fire screen, and a disc of fusible metal closing said passage.

4. In a venting device for gasoline tanks and the like, a tubular member having a plurality of external recesses and provided with means to enable it to be attached to a gasoline tank, a casing threaded to said tubular member, and communicating with said recesses, valve means normally closing said tubular member to prevent the escape of the evaporated gasoline until a predetermined pressure thereof has been reached, and a second valve means associated with the tubular member to allow air to enter the tank when it is being drained, both of said valves opening into said casing, said casing having a passage therein, and a disc of fusible metal closing the passage.

5. In a venting device for gasoline tanks and the like, a tubular member having a plurality of external recesses and provided with means to enable it to be attached to a gasoline tank, a casing threaded to said tubular member, and communicating with said recesses, valve means normally closing said tubular member to prevent the escape of the evaporated gasoline until a predetermined pressure thereof has been reached, and a second valve means associated with the tubular member to allow air to enter the tank when it is being drained, both of said valves opening into said casing, said casing having a passage therein covered by a wire gauze serving as a fire screen.

6. In a venting device for gasoline tanks, a tubular member having a reduced portion externally threaded to enable it to be screwed into a tank, the upper edge of the inner wall of said member being bevelled to provide a valve seat, a first valve resting on said seat and having a

downwardly extending portion provided with a plurality of spaced ribs, resilient means for maintaining said first valve on its seat, said ribs slidably engaging the inner wall of said member, the 5 lower end of said downwardly extending portion being bevelled to provide a valve seat, a second valve engaging said last mentioned valve seat, a valve stem connected to said second valve and extending upwardly through the downwardly extending portion, guide means for said valve stem

mounted on and extending above the first valve, resilient means associated with said guide means for maintaining said second valve on its seat, and a casing threadedly engaging the external wall of said member, said casing enclosing the resilient means of said valve, and the external wall of said member having a plurality of vertical recesses communicating with the interior of the casing.
